CLOTHES SUPPORT

Burt E. Lloyd, Milford, Pa.

Application October 2, 1942, Serial No. 460,471

1 Claim. (Cl. 211—123)

The present invention relates to improvements in clothes supports adapted to hold a plurality of articles of apparel and more particularly to clothes hangers particularly adapted to support clothing including a plurality of trousers.

An important object of the invention is to provide a novel and advantageous clothes hanger of the general character specified.

Another object is to provide a novel form of clothes hanger on which a plurality of trousers may be supported independently.

Another object is to provide a novel form of clothes hanger adapted not only to support a plurality of trousers independently and in compact arrangement but also at least one coat.

Another object is to provide a clothes hanger adapted for use in travelling and having individually movable trousers supports and means for locking said supports in position for convenience in travelling.

Another object of the invention is to provide a clothing hanger in which trousers are supported by independently movable normally parallel supports at different levels and offset laterally in succession from bottom to top to avoid excessive piling up of trousers on lower supports.

A further object of the invention is to provide a novel and advantageous form of clothing support of the so-called "valet" type.

Other objects, features and advantages will appear upon consideration of the following description and of the drawing in which:

Fig. 1 is a perspective view illustrating one embodiment of the invention;

Fig. 2 is a section on the line 2—2 of Fig. 1 with trousers carried by the hanger as indicated in dot-and-dash lines;

Fig. 3 is a fragmentary view in elevation showing the manner of supporting one end of a supporting member for trousers; and

Fig. 4 is a view of the structure of Fig. 3 as viewed from the right.

In Figs. 1, 2, 3 and 4, there is illustrated one embodiment of the invention in which there is a frame comprising upright sides 10 and 11 connected by upper and lower members 12 and 13 respectively which may be in the form of round rods with tapered ends entering corresponding openings in said sides 10 and 11, thus providing wedging connections. Obviously, this arrangement provides a frame which is easily assembled or knocked down. The sides 10 and 11 may take different shapes but as illustrated increase in depth from bottom to top and the rod mem-

bers 12 and 13 enter said sides near the rear edges thereof.

Trouser supports in the form of rods 14 are supported by the sides 10 and 11 adjacent to their front edges. Preferably the supporting means for these rods comprise recesses 15 at the front edges and inner faces of the sides 10 and 11. These recesses 15 are spaced at convenient intervals from top to bottom of the front edges of said sides 10 and 11 and have entrances at said front edges. From said entrances the recesses 15 are inclined downwardly and rearwardly so that when the ends of a rod are inserted in the corresponding recesses the rod will drop to position with its ends in the lower parts of said recesses 15. The recesses 15 are open at the inner faces of said sides 10 and 11 but do not extend to the outer faces of said sides and the rods are thus limited in longitudinal movement to prevent the ends 15 from moving out of the recesses at the inner faces of the sides.

As illustrated in Fig. 2, the supports or rods 14 may be used to support trousers 15b and due to the inclined forward edges of the sides 10 and 11 there is less displacement of the trousers by supports or rods at lower levels or by trousers on said rods at lower levels. If the clothes support with trousers carried thereby is to be moved to another position or packed for moving, the rods 14 may be locked in the recesses by members 16 and 17 pivotally mounted at the tops of sides 10 and 11 respectively so that they can be swung over the entrances of said recesses 15. As illustrated the members or bars 16 and 17 may be pivoted on screws threaded into the sides 10 and 11 and may be provided at their lower ends with slots 18 and 19 to receive screws in the lower parts of the sides 10 and 11 so that the lower ends of the bars 16 and 17 may be held against outward pressure.

The clothes support may be secured to a wall in any suitable manner or may be supported against the wall in any other suitable manner. Preferably there is secured to the top of the support a coat hanger 20 which may comprise a thin curved strip 21 with a hook 22 pivotally mounted in the central part thereof, the end portions of said member 21 being attached to the sides 10 and 11 in a suitable manner as by screws. The clothes support as a whole may be attached to a wall by screws passing through openings 23 in the member 21 and threaded into a wall, door or other suitable support. It will be seen that the bar 21 of the coat hanger serves not only to support the other part of the clothes support but

also to hold the sides 10 and 11 together at the top of the frame. If desired the lower ends of the sides 10 and 11 may be held against spreading by means of a bar 24 similar to bars 16 and 17 connected by screws to the lower ends of the sides 10 and 11. The sides 10 and 11 may be attached to a wall, door or other support by screws passing through openings 25 in the lower ends of sides 10 and 11. It will be evident that instead of securing the clothes hanger to a wall or door by screws or other fastening devices it may be supported by placing the hook 22 on a suitable object such as a nail or hook projecting from a wall, the lower part of the frame then resting against the wall.

When the hook is used in this manner, the coat hanger is available for use. As illustrated in Fig. 1, the sides 10 and 11 may be provided at their tops with recesses 24a to hold an extra member 14 or one which is not in use.

Although the structure described is provided with solid sides 10 and 11, it is obvious that these sides might be made in the form of open work frames having suitable sockets with inner surfaces corresponding to those of recesses 15. It is also evident that the structure of the clothes support might be varied further as to the means of supporting the rods, the important requirement being that the rods or trousers supports 14 will tend to remain in position against movement

away from the sides 10 and 11 and will be limited as to longitudinal movement.

It should be understood that various changes may be made and that certain features may be used without others, without departing from the true scope and spirit of the invention.

What I claim is:

- A clothes support of the class specified, comprising upright sides, means rigidly connecting the sides in spaced relation, independently-movable normally-horizontal trousers supports extending between said upright sides, means for supporting said trousers-supports on said sides and preventing longitudinal movement of said trousers-supports including for one end of each trousers-support a socket in the corresponding upright side and having a closed outer end, an upper entrance to admit the end of the trousers support and a downwardly and rearwardly inclined portion into which the end of the trousers support drops and means for locking such ends in their sockets comprising a holding member pivoted at its upper end to the upright side, for swinging movement substantially in the plane of the front edge of the side to and from a position over the entrances of said sockets where it acts to hold the rod ends in their sockets.
